United States Patent Office.

ISAAC SNIDER, JAMES WOODRUFF, AND J. M. WOODRUFF, OF SALEM, OHIO.

Design No. 3,427, dated March 23, 1869.

DESIGN FOR A STOVE.

The Schedule referred to in these Letters Patent and making part of the same.

To all whom it may concern:

Be it known that we, ISAAC SNIDER, JAMES WOODRUFF, and J. M. WOODRUFF, of Salem, in the county of Columbiana, and State of Ohio, have invented a new and original Design for Stoves; and we do hereby declare that the following is a full, clear, and exact description thereof, reference being had to the accompanying drawings, and to the letters of reference marked thereon, which form a part of this specification.

In the accompanying drawings—

Figure 1 is an elevation of a parlor-stove, with our design thereon.

Letters of reference denote parts.

Commencing from the fender A, and running vertically therefrom, and on each side of the grate A', are panels B, of ogee, or curvilinear shape, in the centre of which are elongated, round-ended leaflets, B¹.

At the top, base, and sides, are four rounded bulbs, B², pointing to each corner; and joining the leaves B¹ are round-ended leaves, B³.

Running horizontally, and joining the bulbs B², are two curved indentations, B⁴, the whole of the panels and their configurations being in relief.

Above the panels B are scrolls C, of an ogee-form, one to each, surmounting which are panels D, of similar shape and configuration as panels B, save being surrounded with a frame-work, D', of a curved section.

The doors of the stove are ornamented with like panels, E, two to each door, all being in relief, above which, and also surmounting the panels D, are panels F, surrounded with a frame, F¹, of a curved section, the configuration contained therein, consisting of a figure, F², of curved outline, composed of semicircles, or segments of the same, with an oblong panel, F³, in the centre of each.

Between these last-named panels are panels, G, of like ornamentation, but not having the surrounding frame, between each of which is a raised figure, H, composed of two outside curved pieces, surrounding a series of scrolls, I; the whole of the above design being in *basso-relievo*.

Having thus described our design,

What we claim as our invention, and desire to secure by Letters Patent, is—

The general configuration and combination of mouldings to form a design for fronts of parlor-stoves, as described and represented.

In testimony that we claim the foregoing as our own, we affix our signatures, in presence of two witnesses.

ISAAC SNIDER.
JAMES WOODRUFF.
J. M. WOODRUFF.
